UNITED STATES PATENT OFFICE

2,501,275

GARBAGE GRINDER, INCLUDING CANTED
ROTARY CUTTING ELEMENTS AND
CANTED FIXED CUTTING MASKS

Richard D. Heller, Tujunga, Calif.

Application October 28, 1946, Serial No. 706,165

14 Claims. (Cl. 241—162)

1

The present invention, though referred to for convenience as a grinder, operates not by reason of any frictional effect, as the term "grinding" infers, but concerns more precisely a machine which by attrition or fretting continuously separates small particles from a larger mass, until the latter is fretted away. The small particles are themselves of appreciable size, so that the operation, strictly speaking, is not pulverization nor comminution, but rather a chewing or slicing away. It is most nearly comparable, in a familiar example, to the "grinding" of meat in a meat "grinder," hence while the invention may itself hereafter be referred to as a grinder, and the operation as grinding, the more exact description above will be implied and understood. The differences in result will be alluded to hereinafter.

In its elemental form the present invention provides a grinder wherein a continuously rotative element cooperates with a second element which may be thought of as fixed, by reason of the angularity of such elements relative to the axis of rotation, and of the rapid changes of angularity of one such element relative to the other as rotation continues, to repeatedly entrap and fret or slice away small particles from a larger mass presented to such elements. In another form several such pairs of elements, to which the mass is somewhat differently presented, operate simultaneously thereupon to grind the mass rapidly into small particles.

It is an object of the present invention to provide means whereby many and varied materials may be chewed away or ground up to small particles for ultimate disposition as such. For example, the present invention is suitable for use as a grinder for garbage or similar waste, so that it may, when ground small enough, be washed away down the drain. In another example the material being ground may be meat, and it may emerge from the grinder in the familiar form of ground beef.

In particular it is an object of the invention to provide such a grinder which will operate, not so much by abrasion as by actual severance or shearing off of small particles extruded between two elements, one of which rotates relative to the other. As an associated object, by this invention the size of the particles can be determined to a degree by the amount of inclination of the plane of the rotative element relative to its axis of rotation, and by its speed of rotation.

In similar fashion a further object is to provide such a grinder capable of progressive grinding to smaller sizes by choice of the diameter, angle of inclination to the axis, and like factors, as between successively encountered rotative disks, with intervening hoppers to hold back discharge of over-size particles until the finer

2

grinding disks act upon them and meter their discharge.

It is also an object to provide such a grinder in which a disk, in addition to operating as indicated above, will effect some degree of abrasion, so that the material may be better presented to the cooperating severing edges of the disk and mask.

The above is by no means an exhaustive tabulation of the objects of the invention, but will serve to afford a sufficiently clear idea, for the present, of the purposes of the invention, and further objects, and the constructional form, and other purposes, will be ascertainable as this specification progresses, or will suggest themselves to one skilled in this art.

The invention is embodied in the novel grinder in the several forms shown in the accompanying drawings, described in this specification, and as will be more particularly pointed out by the claims which terminate the same.

In the accompanying drawings the invention has been shown in several typical forms of arrangement, each suited to effect a particular purpose.

Figure 1 is an axial sectional view through the grinder, arranged for progressive grinding to smaller size, and intended for grinding up kitchen waste or the like, and Figure 2 is a similar view, showing parts, however, after 180° of rotation.

Figure 3 is a face view of a grinder disk, such as is employed in the form of Figures 1 and 2, and Figure 4 is an axial section thereof, substantially along the line 4—4 of Figure 3.

Figure 5 is a vertical axial section through a somewhat more complex form of the grinder, arranged in this instance for grinding meat or the like, and Figure 6 is a transverse vertical sectional view of the same, substantially along the line 6—6 of Figure 5.

In its elemental form the invention is quite simple, involving a rotative shaft 3, driven, for example, by the motor 30, a rotative disk 1 fast thereupon for rotation therewith, as by mounting it upon the noncircular terminal portion 31 of the shaft, and a mask 2, which extends about (in Figures 1 and 2 entirely about) the margin of the disk 1. The disk is substantially circular, but instead of being arranged in a plane normal to the axis of rotation, it is canted or inclined with respect to that axis, and so, when it rotates, it appears to wobble. One high point sweeps through a given orbit, and the opposite high point sweeps through a different orbit, spaced axially from the orbit of the first.

Moreover, the mask 2 is similarly canted, and normally it would be canted in the same plane and to the same degree as the disk 1. The planes of the mask and disk would thus coincide once during each revolution of the disk. At other

times the plane of the disk departs from the plane of the mask, and then approaches the mask's plane again. Thus in Figure 2 the disk is in the same plane with the mask, whereas in Figure 1, after 180° of rotation, the two appear spaced apart, in crossing planes, to leave a gap 10 between them, into which material being ground up can be extruded by pressure from above, or by gravity. The edge 11 of the disk preferably stands up axially, and is sharpened, and likewise the edges 21 of the mask are sharpened, and these edges 11 and 21 cooperate as shears as they approach during rotation, to shear off material extruded into the gap 10. The maximum width of this gap is determined by the angularity in relation to the diameter of the disk, as can be seen at a glance by comparison of the upper and lower disks in Figure 1.

The cutting edge 11 of the rotative disk may be somewhat modified from the even form shown in the lower disk of Figures 1 and 2, in order to magnify and multiply the shearing effect. Thus in Figures 3 and 4 one form of the disk is shown in detail, and here, at 12, the edge 11 rises sharply from a somewhat cut-away area 13 of its end face (see also Figure 1). In addition, for uses where the material to be ground is presented to the end face of the disk, this end face may be somewhat flattened off to a lesser angle relative to the axis, and provided with grooves 14 and transverse or radial notches 15 acting to abrade the material—bones, for instance—presented to this end face, in order that they may the more readily be cut into small portions or particles for extrusion through the gap 10 and severance by the edge 11, 12. Each notch in the edge 11 acts somewhat as a saw tooth, and the edge is relieved behind each notch to permit the mass to approach closer and occupy the space immediately previously occupied by a severed particle.

Before departing from the form shown in Figures 1 and 2 it may be pointed out that the masks 2 are disposed one above the other within a casing 4, including an entrance chute 41 and a waste outlet 42. The material to be ground enters at 41, is guided by the hopper-like casing 4 to the upper and lower disks in turn, and when it passes the latter, is washed out through the outlet 42. Moreover, the lower disk serves to meter the discharge to the outlet 42. Usually its gap 10 is less than the gap at the upper disk (by reason of the lesser diameter or lesser inclination of the lower disk, either or both), and particles severed by the upper disk which are so large that it is undesirable to permit them to pass immediately to the outlet 42 collect in the hopper space between the two disks, and are ground to smaller size by the lower disk, which permits only a metered amount, and pieces of small size, to pass it. This lower disk, by such metering action, smooths out the rate of discharge, preventing the passage of large masses, even of soft material, which might tend to choke the outlet or drain, and thus it maintains a more regular rate of discharge, even though the upper disk, because it must have the capacity to grind up hard materials rapidly, would tend to pass softer materials so much more rapidly that, unchecked, they might have such a clogging tendency.

Provision may be made for continuously supplying water to wash away the ground up material, if desired, but since this is no part of the present invention it has not been illustrated. The assembly illustrated facilitates disassembly for access to the interior, or for replacement of

worn parts, or a disk and mask of different diameter or inclination can be substituted, if finer or coarser final grinding is desired, or a different metering rate.

5 The form of the device in Figures 5 and 6 is the same in principle, except that a plurality of the disks 1 is provided, closely spaced along the shaft 3 or along the noncircular portion 31 thereof, which in this instance is supported horizontally in bearings 43 in the hopper-like casing 4. The masks 2 are similarly closely spaced, and both the disks and masks are canted, though maintained preferably in parallel planes. The masks do not, in this form, each extend completely about 10 the periphery of its disk, but only part way, or, as shown, about half way around the disk, and the material may enter between the disks and at one end of the set of masks. The spacing of the disks is such, with respect to their inclination and 15 diameter, that the high portion at one side of a given disk will sweep through the orbit of the opposite high portion of the adjoining disk, and similarly the other high point of the given disk will sweep the orbit of the adjoining disk 20 at its side. This is shown best by the dot-dash lines in Figure 5.

25 Material presented to this form of the device will be engaged by many disks, will be carried in the direction of rotation shown by the arrow 30 in Figure 6, and will be extruded between the disks and the masks, which latter in this instance form a sort of grillwork closing the bottom of the hopper 4. In addition a deflector 44 may be employed to guide the downwardly moving material into the disks. When the material has been 35 ground up it will be received in the drawer or receiver 45, whence it can be removed when all the material has been ground.

It is desired to point out that the disks appear 40 completely circular when viewed axially. Actually they are not exactly circular, but somewhat elliptical, as must be true when it is remembered that they are inclined with respect to their axis of rotation, and yet the sweep of their margins defines a cylinder of revolution. Their marginal edges, moreover, should lie preferably in this cylinder of revolution, that is, parallel to the axis of rotation, and not perpendicular to the end face of the disk. Each disk has severing edges upon 45 its opposite faces, in part for better balance, but also in order that when one edge 11 becomes dull the disk can be turned over to present the opposite sharp edge.

50 In the usual design the disks will be rotative and the masks stationary, but in principle it is only necessary that there be relative rotation therebetween. There is no reason why the masks may not rotate, oppositely to the disks, or in the same sense but at a speed differing from the 55 rotative speed of the disks, or even in the absence of rotation of the disks. Such variants afford the possibility of widely varying the size of the chewed-off particles without variation of the diameter, slant, speed, or other characteristics of the disks.

60 At the outset of this specification an analogy was drawn between the present device and the conventional meat grinder. It is now clear that the present device is distinguishable, in its effect, 65 from a meat grinder, in that the meat particles are not, as in the conventional meat grinder, mashed and the cells broken down, with the juice expressed and lost, and the ground mass left with a rather negative flavor, but rather in the present 70 device the particles are individually severed 75

cleanly from the mass, by a slicing cut, leaving the juice in them, and retaining the distinctive flavor and palatability of the original meat.

I claim as my invention:

1. A grinder comprising a disk the plane whereof is canted relative to an axis of rotation which extends through the center of the disk, and a coaxial mask the peripheral edge whereof closely surrounds the disk, and which is similarly canted relative to such axis, means to effect relative rotation between the mask and disk about such axis, the thickness of the disk and mask at their peripheral edges, and their respective angles of cant, being such as to open a gap between their peripheral edges when the two are in a first, oppositely canted rotative position, and to close such gap by relative rotation to a second rotative position 180° removed from the first, and means so to effect such relative rotation, and thereby to effect repeated opening and closing of such gap.

2. A grinder as in claim 1, wherein the cooperating peripheral edges of the disk and mask are sharp, to engage and shear off interposed material as the gap closes.

3. A grinder as in claim 1, wherein the angles of cant of the disk and mask are substantially identical, and they are disposed relatively, along the axis of rotation, to substantially coincide in plane in the second rotative position.

4. A grinder as in claim 1, wherein the mask is stationary and the disk is rotative.

5. A grinder as in claim 1, including a housing disposed in advance of the disk and mask, formed and arranged to contain and present material to the recurrently opening and closing gap.

6. A grinder comprising a material-containing and guiding housing including a mask having an aperture which, when viewed in the direction of an axis of rotation, is circular, the peripheral edges whereof define a plane which, when viewed from one side, is canted relative to such axis, and which edges are thinner than half the distance between their points of greatest separation in the axial direction, a rotative disk of similar thinness, of similar cant, and which, when viewed in the direction of such axis, is generally circular and of a diameter which closely approximates that of the mask's aperture, the disk being located to substantially coincide with the plane of the edges of the mask's aperture, when in a first rotated position, and to be spaced therefrom to define gaps above and below the mask's aperture in a second position rotated 180° from the first position, and means so to rotate the disk, to repeatedly open and close such gaps.

7. A grinder as in claim 1, wherein the end face of the disk at one side of a diameter lies more nearly in a plane normal to the axis than the disk as a whole, and is roughened to abrade a mass presented thereto.

8. A grinder as in claim 7, wherein the disk margin leading to such roughened area is formed as an upstanding marginal rib faired into the margin of such roughened area.

9. A grinder as in claim 1, including a second disk spaced axially below the first disk and also canted relative to the same axis, a second mask similarly arranged relative to said second disk, said second disk and mask being organized and arranged to pass only particles smaller than the maximum size that will pass the upper disk and mask, means to effect relative rotation between

the second disk and mask, conjointly with the first, and casing means to lead material to be ground in succession to the upper and then to the lower mask.

5 10. A grinder as in claim 9, wherein the lower disk and mask are canted at substantially the same angle relative to the axis as are the upper disk and mask to such axis but are of lesser diameter, whereby the maximum gap between the cooperating peripheries of the second disk and its mask is less than the corresponding gap between the upper disk and its mask.

15 11. A grinder as in claim 9, wherein the two disks are rotative and their masks are stationary, and characterized in that the two disks and masks are mutually oppositely canted relative to the axis of rotation.

20 12. A grinder comprising a rotative shaft, a plurality of circular disks closely spaced therealong and fast thereto, all said disks having their planes canted in the same direction and by like amounts relative to the shaft's axis, a fixed mask closely embracing the periphery of each disk, and canted similarly to its disk in one position of the latter, and cooperating with the margin of its disk for severing particles from a mass presented to said disks and their masks.

25 13. A grinder comprising a rotative shaft, a plurality of circular disks closely spaced therealong and fast thereto, all said disks having their planes canted in the same direction and by like amounts relative to the shaft's axis, a fixed mask closely embracing the periphery of each disk, and canted similarly to its disk, to come into planar coincidence therewith in one position of the latter, and cooperating with the margin of its disk to open a gap therebetween by rotation 180° beyond such position of planar coincidence, for severing particles from a mass presented to said disks and their masks, the axial spacing of the disks being such, relative to their canting upon the shaft, that one portion of an intermediate disk's periphery sweeps within the orbit of the adjoining disk at one side, and a second portion of the intermediate disk's periphery sweeps within the orbit of the adjoining disk at the opposite side.

40 14. A grinder comprising a hopper-like casing, a rotative shaft horizontally disposed transversely across its bottom, a plurality of circular disks, having sharp marginal edges, closely affixed along said shaft for rotation thereby, all said disks lying in parallel planes canted relative to the shaft's axis by an amount in excess of the thickness of such disk, and a like number of sharp-edged masks, one to each disk of similar thickness and similarly canted, embracing the lower portion of the periphery of said disks.

Certificate of Correction

Patent No. 2,501,275

March 21, 1950

RICHARD D. HELLER

It is hereby certified that errors appear in the printed specification of the above numbered patent requiring correction as follows:

Column 6, line 8, after "axis" insert a comma; line 56, strike out the comma and words ", one to each disk" and insert the same in line 57 after the syllable "ness" and before "and"; same line 57, before "and" insert a comma;

and that the said Letters Patent should be read with these corrections therein that the same may conform to the record of the case in the Patent Office.

Signed and sealed this 20th day of June, A. D. 1950.
